UNITED STATES PATENT OFFICE.

GEORGE W. COHEN, OF ALLEGHENY, PENNSYLVANIA.

CURTAIN-SUPPORT RING.

SPECIFICATION forming part of Letters Patent No. 740,090, dated September 29, 1903.

Application filed December 28, 1902. Serial No. 136,723. (No model.)

To all whom it may concern:

Be it known that I, GEORGE V. COHEN, a citizen of the United States, residing at Allegheny, in the county of Allegheny and State of Pennsylvania, have invented a new and useful Improvement in Curtain-Support Rings, of which improvement the following is a specification.

This invention relates to new and useful improvements in curtain-support rings.

The invention has for its object the provision of a simple and comparatively inexpensive pole-ring whereby the curtain is supported and easily and quickly attached and detached.

In the accompanying drawings I have by various views illustrated my improved ring and the manner in which the same is employed in practice, in which drawings—

20 Figure 1 is an end view of a curtain-pole in section, showing the ring thereon and the application of the curtain to the ring. Fig. 2 is a front view of the same. Fig. 3 is a side view of the ring, partly in section, as it would appear when not in use. Fig. 4 is a rear view of said ring. Fig. 5 is a vertical sectional view through the ring.

Further reference to said views, collectively, for a detailed description of the improved ring, the numeral 1 designates the curtain-pole, 2 the curtain, and 3 the ring.

The ring is formed from a strip of sheet metal of concavo-convex form in cross-section, bent at its middle to form a ring, one extremity 4 of said strip being flattened and provided with an elongated opening 5, while the other extremity 6 is formed in a reverse concavo-convex form in cross-section from that of the body and provided with the small 35 oppositely-extended bands 7 for securing the curtain-supporting hook 8 thereto, said bands being formed into the strip end by slitting the metal laterally and forcing the same into the desired form by means of a suitable punch or press. The extremities of the ring-strip are bent into an approximately parallel position or in line with the ring center, and to the inner side of the concavo-convex extremity at the said bands 7 is firmly soldered the said 45 curtain-supporting hook 8, so that the point will project through the elongated opening in the other extremity, said concavo-convex ex-

tremity being also provided upon its outer face with a rosette 9 for ornamental purposes.

In practice a number of the rings are employed upon the pole and the curtain suspended at intervals by the ring-hooks, the extremities 4 of all of the rings being of sufficient resilience as to clamp the curtain to the hooks, as shown at Fig. 1, when applied. If desired, the slotted bands in the concavo-convex extremity may be dispensed with and the hooks soldered direct thereto.

A curtain-support ring of this character is easily and quickly applied to the curtain, can be manufactured at nominal cost, and will be found very serviceable.

Having thus fully shown and described my invention, what I claim as new, and desire to secure by Letters Patent, is—

1. A curtain-support adapted for use with curtain-poles, comprising a strip of metal having an opening in one extremity and bent at its middle into a ring to engage on the pole both extremities of said strip projecting from the ring in approximate parallel relation, and a hook on the imperforated extremity to extend through the opening in the other adapted to pass through and support the curtain.

2. A curtain-support adapted for use with curtain-poles, comprising a strip of metal having an opening in one extremity and bent at its middle into a ring to engage on the pole both extremities of said strip projecting from the ring in approximate parallel relation, and a hook on the imperforated extremity to extend through the opening in the other adapted to pass through and support the curtain, said ring portion of the strip being of concavo-convex form in cross-section.

3. A curtain-support adapted for use with curtain-poles, comprising a strip of metal having an opening in one extremity and bent at its middle portion into a ring to engage on the pole both extremities of said strip projecting from the ring portion in approximate parallel relation, and a hook on one of said extremities to extend through the opening in the other to support the curtain, said ring portion of said strip being of concavo-convex form in cross-section and the hook extremity of reverse concavo-convex form.

4. A curtain-support adapted for use with curtain-poles, comprising a strip of spring

metal having an opening in one extremity and bent at its middle into a ring to engage on the pole both extremities of said strip projecting from the ring in approximate parallel relation, and a hook on the imperforated extremity to extend into the opening in the other adapted to pass through and support the curtain, said extremity with the opening therein adapted to yield and clamp the curtain to said hook.

5. A curtain-support adapted for use with curtain-poles, comprising a strip of spring metal having an opening in one extremity and slotted keepers on the other and bent at its middle portion into a ring to engage on the pole both extremities projecting from the ring portion in approximate parallel relation, and a hook secured to the keepers on one of said extremities to extend into the opening of 15 the other to support the curtain, said extremity with the opening therein adapted to yield and clamp the curtain to said hook.

20. A curtain-support adapted for use with

curtain-poles, comprising a strip of spring metal having an opening in one extremity 25 and slotted keepers on the other and bent at its middle portion into a ring to engage on the pole both extremities of said strip projecting from the ring portion in approximate parallel relation, and a hook secured to the 30 keepers on one of said extremities to extend into the opening in the other to support the curtain, said extremity with the opening therein adapted to yield and clamp the curtain to said hook, said ring being concavo- 35 convex in cross-section and the hook-carrying extremity of opposite but like form in cross-section.

In testimony whereof I have hereunto signed my name in the presence of two subscribers.

GEO. W. COHEN.

In presence of—

RICHARD S. HARRISON,
M. B. BATES.
